(57) **CLAIM**

The ornamental design for a sink mixer pull out, as shown and described.

DESCRIPTION

FIG. 1 is a front perspective view of a sink mixer pull out according to the present invention.

FIG. 2 is a front view of the sink mixer pull out of FIG. 1.

FIG. 3 is a rear view of the sink mixer pull out of FIG. 1.

FIG. 4 is a left side view of the sink mixer pull out of FIG. 1.

FIG. 5 is a right side view of the sink mixer pull out of FIG. 1.

FIG. 6 is a top view of the sink mixer pull out of FIG. 1; and, FIG. 7 is a bottom view of the sink mixer pull out of FIG. 1.

The dashed lines illustrate environment that does not form a part of the present invention, and no claim is made to the material illustrated with dashed lines.

The broken lines showing of the bottom portion, the tip of the spout and the parallel broken lines at the base of the shaft of the sink mixer are included for the purpose of illustrating a portion of the sink mixer and forms no part of the claimed design.

The sink mixer is shown with a symbolic break in its length. The appearance of any portion of the article between the break lines forms no part of the claimed design.
